UNITED STATES PATENT OFFICE

172,457

BOOKHOLDER

Harold James Balmer, Lansing, Mich.

Application April 3, 1953, Serial No. 24,354

Term of patent 7 years

(Cl. D33—3)

To all whom it may concern:

Be it known that I, Harold James Balmer, a citizen of the United States of America, residing at city of Lansing, county of Ingham, State of Michigan, have invented a new, original, and ornamental Design for a Bookholder, of which the following is a specification, reference being had to the accompanying drawing, forming a part hereof.

Figure 1 is a side elevation view of a bookholder, showing my new design.

Figure 2 is a top plan view thereof.

Figure 3 is an end elevational view thereof taken from the left of Figure 1.

Figure 4 is an end elevational view thereof taken from the right of Figure 1.

I claim:

The ornamental design for a bookholder, as shown.
